AUTOMATIC STEERING DEVICE FOR BEAN PICKING MACHINES

John W. Ward, Vernon, N. Y., assignor to Ward Canning Company, Vernon, N. Y., a partnership

Application April 1, 1948, Serial No. 18,335

6 Claims. (Cl. 97—49)

1

My invention relates to an automatic steering device for a bean picking machine.

The object of the invention is to provide an automatic steering device for a bean picking machine such as described more particularly in a co-pending application of Leila B. S. Ward filed in the Patent Office on the 12th day of February, 1948, Serial Number 7,830. This device is designed to keep the front wheels of the bean picker in line with the rows of bean vines.

Heretofore stones or other obstructions in the line of the front wheels of the bean picker diverted said wheels from a direct path. To overcome this objection is the purpose of the present invention.

The object will be understood by referring to the drawings in which

Fig. 1 is a fragmentary view of the front part of the frame of a bean picker with the automatic means for steering the wheels applied thereto.

Fig. 2 is a detail view enlarged showing a horizontal section taken on the line 2—2 of Fig. 3.

Fig. 3 is a detail view enlarged showing a vertical section of a valve and casing employed in the device.

Fig. 4 is a detail view enlarged similar to the view of Fig. 3 showing the valve at right angles to its position illustrated in Fig. 3.

Fig. 5 is a diagrammatic view of the oil pressure system employed.

Referring more particularly to the drawings, Fig. 1 is the front part of the frame of a bean picking machine comprising a cross angle iron 1 supported at opposite ends by angle irons 2, 3 and 4. Angle irons 2, 3 and 4 are welded to cross horizontal angle iron 1.

A bar 6 is attached to one side of angle iron 1 by bolts 7. Outstanding spaced lugs 8, 8 having journals 9, 9 are formed integral with bar 6 and are located adjacent one end thereof.

A shaft 10 held in place by cotter pins 11, 11 is projected through journals 9, 9 and also through tongue 12 which turns freely thereon.

A bearing 13 is formed integral with the outer free end of tongue 12. A shaft 14 is carried in bearing 13 and held therein by cotter pins 15, 15 disposed therethrough at either end thereof. Shaft 14 projects through aligned apertures in the upper bar 16 and lower bar 17 of clevis 18 and allows the clevis 18 to turn thereon.

A pin 19 is used with clevis 18 to hook the bean picker to the rear end of a tractor.

The means for turning clevis 18 on its shaft 14, whereby to automatically steer the bean picker contemplates a yoke 20 welded to the lower

frame bar 17 of clevis 18. The opposite free ends of yoke 20 are pivoted at 21, 22 to the bifurcated ends of piston rods 23 and 24 by pins held in place by cotter pins 25.

Pistons 26, 26 are formed integral with each of the piston rods 23 and 24 and operate in cylinders 27, 28 which are disposed in parallel relation to each other and to tongue 12.

Moreover, each of the cylinders 27 and 28 has rearwardly extending a pair of spaced lugs 29, 29 for the interposition of lug 30 extending laterally and formed integral with the sides of tongue 12. Lugs 29 are pivoted to lug 30 by a shaft 31 held in place by cotter pins 32, whereby to allow said cylinders 27 and 28 to rock relative to tongue 12.

The means for supplying oil or other motive power to cylinders 27 and 28, whereby to actuate pistons 26, 26 therein, contemplates the fluid system shown particularly in Fig. 5 and comprises a valve casing 35 having a bracket 36 for bolting it to bar 6 at 37. Valve casing 35 is connected to cylinder 27 by flexible hose 38 and to cylinder 28 by flexible hose 39. Hose 38 runs from port 40 of valve casing 35 to port 41 of cylinder 27, whereas hose 39 runs from port 42 of casing 35 to port 43 of cylinder 28. A hose 45 connects some source of supply 46 to port 47 of valve casing 35, whereby to supply fluid under pressure by pump 48 to casing 35. The return flexible hose 49 connects port 50 with said source of supply 46. The fluid system has also a relief line 51 with a relief valve 52 therein and also a metering valve 53.

The means for controlling the flow of oil alternately to cylinders 27 and 28 embodies valve 54 mounted to turn in cylindrical valve casing 35. As shown in Figs. 2, 3 and 4, valve 54 is in the form of a cylinder having shoulders at 55, 55 resting against the anti-friction members 56, 56 housed in end members 57, 57 of valve casing 35. Members 57 are held to casing 35 by screw bolts 58.

Valve 54 is formed in cylindrical rod 59 by cutting away the opposite sides thereof to leave a narrow connecting part, that will open passageways from port 47 to port 42 and port 40 to port 50 when turned to dotted line position illustrated in Fig. 2 and close said ports in full line position shown therein. Also when turned at right angles to dotted line position it will open passageways from port 47 to port 40 and from port 42 to port 50.

The means for actuating valve 54, whereby to open and close said ports, contemplates flexible buffer rods 60 and 61 which lie in a horizon-

tal plane and at an angle to each other, whereby to converge towards the rear.

Rod 60 is projected through and welded to an aperture in the lower extended part 54' of valve 54, whereas rod 61 is mounted in a similar manner to the lower end of shaft 62.

Valve 54 also extends upward beyond end member 57 to which is attached to turn therewith the sleeved part 63 of crank arm 64 by set bolt 65. Shaft 62 has a bearing in sleeve 66 and turns loosely therein.

Sleeve 66 has members 67, 67 which are welded to bar 6.

The sleeved part 68 of crank arm 69 is attached to and turns with the upper end of shaft 62 by set bolt 70. A tie rod 71 having bifurcated ends 72, 72 is fulcrumed at said ends to the free ends of crank arms 64 and 69 by pivot pins 73, 73 held in place by cotter pins 74. The movement of either buffer rod 60 or 61 will turn valve 54 relative to said ports in casing 35.

The means for automatically returning valve 54 to full line position illustrated in Fig. 2, whereby ports 41, 40 and 50 and 42 will be closed, embodies coiled springs 80 and 81 mounted on tie rod 71. Said springs 80 and 81 are separated by forks 82, 82 extending laterally from and formed integral with upstanding bracket 83 which is bolted at 84, 84 at its lower end to bar 6. Said forks 82, 82 span tie rod 71. Adjustable collars 85, 85 are mounted on rod 71 and are held in place by winged screws 86, 86. Said springs 80 and 81 tend to hold tie rod 71 in neutral or full line position shown in Fig. 1.

Tongue 12 is held in horizontal position by a rod 215 having a sleeve 216 for the projection of shaft 217 that has bearings in upstanding parallelly disposed space rails 218, 218 formed integral with the top surface of tongue 12. Cotter pins 220 are used to hold shaft 217 in place. Rod 215 has its other end attached to the chassis of the bean picker.

The operation of the device is effected when the said bean picker, not shown, moves through the rows of vines by the flexible buffer rods 60 and 61 coming in contact with the vines of said beans.

Assuming that rod 61 makes contact with an out of line row of vines to the right of the row, in this instance rod 61 will turn shaft 62 clockwise and thereby move the connected parts, namely crank arm 69, tie rod 71, crank arm 64 clockwise or to the right in Fig. 1.

The movement of crank arm 69 will cause valve 54 to turn clockwise to open passageways from supply port 41 to port 42 of casing 35 and also open the passageway from port 40 to return port 50 of casing 35. This will allow the oil to enter cylinder 28 to push piston 26 towards the front thereof and thereby piston rod 24 will push on yoke 20 to rock clevis 18 clockwise or towards the left. At the same time the oil in cylinder 27 will escape back through hose 38 and from port 40 to return to port 50 of casing 35 back through hose 49 to supply tank 46.

Immediately the bean picker has returned to a straight line position with the rows of vines, coiled spring 80 being under tension will move tie rod 71 to the left illustrated in Fig. 1, whereby to restore valve 54 to closed or full line position illustrated in Fig. 2.

When flexible buffer rod 60 is moved by coming in contact with an out of line row of vines, the reverse movement of the aforesaid parts will occur to turn valve 54 to open passageways from

5 supply port 41 to port 40 and from port 42 to return port 50 and hence the piston 26 in cylinder 27 will be moved forward to rock clevis 18 counter-clockwise to move the bean picker to the right. In this instance spring 81 being under tension will restore valve 54 to its closed position. It will be observed that as one of the pistons 26 goes forward under pressure of the fluid the other will retreat and vice versa.

Having thus described my invention, what I claim as new and desire to secure by letters patent is as follows:

1. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders and with a source of fluid under pressure, a valve mounted in said casing, movement of said valve in one direction being adapted to open ports to supply fluid under pressure to one of said cylinders and movement of said valve in the opposite direction to the other cylinder, a pair of buffer rods adapted to contact the opposite sides of a row of bean vines and to be moved outward by the bean vines when the relationship between the bean picking machine and the row of bean vines changes, and means connecting each of said buffer rods to said valve for moving said valve in one of two opposite directions upon outward movement of one or the other of said buffer rods, whereby movement of said buffer rods by the bean vines in the row admits fluid to one or the other of said cylinders to turn said yoke member and steer the machine.

2. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders and with a source of fluid under pressure, a rotary valve mounted in said casing, rotation of said valve in one direction being adapted to open ports to supply fluid under pressure to one of said cylinders and rotation of said valve in the opposite direction to the other cylinder, a pair of buffer rods adapted to contact the opposite sides of a row of bean vines and to be moved outward by the bean vines when the relationship between the bean picking machine and the row of bean vines changes, one of said buffer rods being connected to said valve for rotating said valve in one direction upon outward movement of said buffer rod, and the other of said buffer rods being intermediately connected to said valve for rotating said valve in the opposite direction upon outward movement of said other buffer rod, whereby movement of said buffer rods by the bean vines in the row admits fluid to one or the other of said cylinders to turn said yoke member and steer the machine.

3. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders

and with a source of fluid under pressure, a rotary valve mounted in said casing, rotation of said valve in one direction being adapted to open ports to supply fluid under pressure to one of said cylinders and rotation of said valve in the opposite direction to the other cylinder, a pair of buffer rods adapted to contact the opposite sides of a row of bean vines and to be moved outward by the bean vines when the relationship between the bean picking machine and the row of bean vines changes, one of said buffer rods being connected to said valve for rotating said valve in one direction upon outward movement of said buffer rod, a tie rod connected at one end to said valve, a shaft connected to the opposite end of said tie rod and to the other of said buffer rods, whereby outward movement of said other buffer rod will rotate said valve in the opposite direction, whereby movement of said buffer rods by the bean vines in the row admits fluid to one or the other of said cylinders to turn said yoke member and steer the machine, and springs associated with said tie rod for normally holding said valve in neutral position.

4. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders and with a source of fluid under pressure, a rotary valve mounted in said casing, rotation of said valve in one direction being adapted to open ports to supply fluid under pressure to one of said cylinders and rotation of said valve in the opposite direction to the other cylinder, a pair of buffer rods adapted to contact the opposite sides of a row of bean vines and to be moved outward by the bean vines when the relationship between the bean picking machine and the row of bean vines changes, one of said buffer rods being connected to said valve for rotating said valve in one direction upon outward movement of said buffer rod, a crank arm connected to said valve, a tie rod connected at one end to said crank arm, a second crank arm connected to said tie rod at the opposite end thereof, and a shaft connected to said second crank arm and to the other of said buffer rods, whereby outward movement of said other buffer rod will rotate said valve in the opposite direction, whereby movement of said buffer rods by the bean vines in the row admits fluid to one or the other of said cylinders to turn said yoke member and steer the machine.

5. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders and with a source of fluid under pressure, a rotary valve mounted in said casing, rotation of said valve in one direction being adapted to open ports to supply fluid under pressure to one of said cylinders and rotation of said valve in the opposite direction to the other cylinder, a pair of buffer rods adapted to contact the opposite sides of a row of bean vines and to be moved outward by the bean vines when the relationship between the bean picking machine and the row of bean vines changes, one of said buffer

rods being connected to said valve for rotating said valve in one direction upon outward movement of said buffer rod, a crank arm connected to said valve, a tie rod connected at one end to said crank arm, a second crank arm connected to said tie rod at the opposite end thereof, a shaft connected to said second crank arm and to the other of said buffer rods, whereby outward movement of said other buffer rod will rotate said valve in the opposite direction, whereby movement of said buffer rods by the bean vines in the row admits fluid to one or the other of said cylinders to turn said yoke member and steer the machine, and springs associated with said tie rod for normally holding said valve in neutral position.

6. In an automatic steering device for a bean picking machine, a yoke member adapted to steer the machine when turned to one side or the other, piston rods pivotally connected to opposite sides of said yoke member, pistons mounted on said piston rods, cylinders housing said pistons, a valve casing having ports therein, conduits connecting said casing ports with said cylinders and with a source of fluid under pressure, a rotary valve mounted in said casing, rotation of said valve in one direction being adapted to open ports to supply fluid under pressure to one of said cylinders and rotation of said valve in the opposite direction to the other cylinder, a pair of buffer rods adapted to contact the opposite sides of a row of bean vines and to be moved outward by the bean vines when the relationship between the bean picking machine and the row of bean vines changes, one of said buffer rods being connected to said valve for rotating said valve in one direction upon outward movement of said buffer rod, a tie rod connected at one end to said valve, a shaft connected to said tie rod at the opposite end thereof, a second crank arm connected to said tie rod and to the other of said buffer rods, whereby outward movement of said other buffer rod will rotate said valve in the opposite direction, whereby movement of said buffer rods by the bean vines in the row admits fluid to one or the other of said cylinders to turn said yoke member and steer the machine, coil springs mounted on said tie rod, a member separating said springs, and collars mounted on said tie rod to hold said springs under compression, whereby said valve is normally held in neutral position.
